ELECTRIC COFFEEPOT OR SIMILAR ARTICLE

Fred C. Schwanek and Jack Morgan, Chicago, Ill., assignors to Dormeyer Corporation, Chicago, Ill., a corporation of Illinois

Application November 12, 1954, Serial No. 33,079

Term of patent 14 years

(Cl. D44—26)

Fig. 1 is a side elevational view of an electric coffeepot or similar article showing my new design, and Fig. 2 is a top plan view thereof.

The side opposite that shown in Fig. 1 is substantially like the side shown in Fig. 1.

I claim:

The ornamental design for an electric coffeepot or similar article, as shown and described.
